(57) **CLAIM**

We claim the ornamental design for a power nozzle for a vacuum, as shown and described.

DESCRIPTION

FIG. 1 is a perspective view of a power nozzle for a vacuum showing our new design;

FIG. 2 is a top plan view thereof;

FIG. 3 is a front view thereof;

FIG. 4 is a rear view thereof;

FIG. 5 is a side view thereof;

FIG. 6 is an opposite side of FIG. 5;

FIG. 7 is a bottom plan view thereof; and,

FIG. 8 is a perspective view thereof, showing the environmental structure in broken lines.

The portions of the drawing figures shown in broken lines form no part of the claimed design.
